UNITED STATES PATENT OFFICE.

EARL B. CALDERWOOD, OF OAKLAND, CALIFORNIA.

COMBINATION DOORKNOB AND RINGING DEVICE.

Application filed June 12, 1922. Serial No. 567,799.

To all whom it may concern:

Be it known that I, EARL B. CALDERWOOD, a citizen of the United States, and a resident of Oakland, county of Alameda, and State 5 of California, have invented a new and useful Combination Doorknob and Ringing Device, of which the following is a specification.

The present invention relates to improvements in combination door knobs and ringing devices, and its particular object is to provide a ringing device hidden in a door knob that will sound an alarm when the door knob is turned in either direction for 10 the purpose of opening the door. My combination is intended to be used especially for inside doors and is constructed in such a manner that its outer appearance does not in any way indicate that a ringing device is 15 connected therewith. Simple means are provided for rendering the ringing device operative or inoperative according to the wishes of the inhabitant of the house employing my door knobs.

The preferred form of my invention is illustrated in the accompanying drawing, in which Figure 1 shows a perspective outside view of my door knob; Figure 2 a view in side elevation partly in cross section; Figure 3 an end view looking at it from the outside, with the bell removed and a portion shown in section substantially along line 3-3 of Figure 4; Figure 4 a cross section substantially along line 4-4 of Figure 3; Figure 5 an end elevation of the ringing device looking at it from the opposite side to that of Figure 3; Figure 6 a perspective detail view of a locking element; Figure 7 a detail view of a disc co-operating with said locking element; Figure 8 an end view of a flange collar and Figure 9 a side elevation of the same. While I have shown only the preferred form of my invention I wish to have it understood that various changes or 40 modifications may be made within the scope of the claims hereto attached without departing from the spirit of the invention.

My device comprises in its principal features a stationary member (1), a ring (2) actuating the door latch, a bell (3) and a ringing mechanism inside of the bell.

The stationary member (1) is rigidly secured to a collar (4) having a flange (6) thereon which is provided with a plurality 55 of points (7) adapted to grip the wood (8) of the door (9) so as to hold the collar

against rotation. A plate (11) secured to the door by means of screws (12) and bearing on the surface of the flange (6) holds the same firmly to the door.

The door latch (13) is actuated by means of the ring (2) which is provided for this purpose with a central shaft (14) secured in one closed end (16) of the ring, and provided with a longitudinal perforation (17) of square cross section adapted to engage the square member (18) connected by means not shown, with the door latch and adapted to operate the same on a right hand as well as on a left hand turn.

A screw (19) adapted to be inserted through a hole (21) in the stationary member secures the shaft (14) to the member (18), the closed end (16) of the ring (2) bearing on the outer end of the stationary member (1). The ring (2) may actuate the door latch on a right hand turn or a left hand turn of about 90 degrees in the usual manner, spring means being associated with the latch for returning the ring (2) to its initial position when the pressure on the same is released. Since no novel features are claimed for the latch as such its operating mechanism is not shown in the drawing.

The outer end of the shaft (14) is provided with a recess (22) adapted to receive one end of the shaft (23) supporting the driving mechanism for the ringing device. The other end of this shaft (22) is threaded as shown at (23) and adapted to receive the internally threaded hub (24) of the bell (3), the marginal portion (26) of which extends into the ring (2) as shown in Figure 2.

The ringing mechanism is supported between the closed end (16) of the collar (2) and a plate (27) secured thereto in parallel and spaced relation by spacing pins (28). A spiral spring (29) having one end secured to the shaft (22) and the other end to one of the spacing members (28) as shown in Figure 5 serves as the driving means for the ringing mechanism. It is placed under tension by rotating the bell (3) clockwise and normally locked in that position by the locking member (31), shown in detail in Figure 6, which co-operates with a disc (32) mounted on the shaft in fixed relation to the ratchet (33), which will be described hereafter. The disc (32) shown in detail in Figure 7 is provided with a peripheral notch (33) adapted to be engaged by a tongue (34) projecting from the locking member (31). When this

tongue is engaged with the notch it prevents the disc from rotating and the tongue and the notch are normally kept in engagement by means of the spring (36) connecting the 5 far end (37) of the locking member with the spacing member (28).

The locking member is disengaged from the disc so as to allow the ringing mechanism to become operative by the co-operation of a 10 curved flange (37) on the locking member extending through a slot (38) in the closed end of the collar, with the stationary rod (39) supported in the stationary member (1). When the ring is turned for the purpose of opening the door the curved under surface of the flange (37) rides on the stationary rod (39) and thereby lifts the locking member out of its engagement with the 15 notch (33) in the disc (32), thus allowing the spring (29) to operate the ringing mechanism. The rod (39), as shown in Figure 2, forms an arm of the crank (41) supported in the stationary member (1), and if the latter crank is turned the rod is thereby moved 20 into an inoperative position thus allowing the ring to be turned for the purpose of opening the door without ringing the bell.

The ringing mechanism itself is simple in construction. As shown in Figure 3, it comprises a ratchet (42) rigidly secured to the 30 shaft (28) allowing the latter to be turned clockwise for the purpose of winding the spring, but engaging on a counter-clockwise turn the gear wheel (43) through the pawl (44). The latter gear wheel is connected through the pinion (46), the gear wheel (47) and the second pinion (48) with the toothed 35 wheel (49), which latter operates the pallet (51) pivoted on the transverse pin (52) in the manner of an escapement, causing the 40 same to oscillate on the pivot and to set in motion the hammer (53) which strikes the bell in rapid succession.

The operation of the device will be readily 45 understood from the foregoing description. To wind the ringing device it is only necessary to turn the bell clockwise. Due to the ratchet arrangement this turning motion will not effect the ringing device but will tend to set the spring. The latter would tend to turn the shaft (23) counter-clockwise but in doing so it would have to turn the ringing mechanism including the disc (32). As soon however, as the notch (33) in the disc (32) passes underneath the tongue (34) of the locking member (31), it is engaged by the 55 same due to the action of the spring (36) and the ringing device is thereby locked. If a person in the attempt to open the door turns the ring (2), the curved flange (37) of the locking member (31) rides on the rod (39) secured in the stationary member (1) and is lifted out of its engagement with the disc (33) thereby releasing the ringing 60 device, which now becomes active. When the

rod (39) has been passed by the flange (37) the spring (36) will again force the tongue (34) to engage the notch in the disc (32) as soon as the latter passes the tongue, so that the device is locked automatically after it 70 has been allowed to ring for a certain length of time, corresponding in both cases to the period of one turn of the disc. If it is desired to render the device inoperative altogether it is only necessary to turn the crank 75 (41), whereby the rod (39) is removed from the flange (37) a sufficient distance so as not to engage the same.

The locking member (31) is provided with two slots (56) and (57) engaging and riding on the shafts (23) and (58) respectively, which latter shaft serves as a support for the toothed wheel (49). The flange (37) is furthermore provided with a projecting point (59) adapted to engage the teeth of the 80 wheel (49) at the same time the tongue (34) engages the notch (33) of the disk (32), whereby the device is locked in two places 85 instead of one.

I claim:

1. A device of the character described, comprising a door knob, a spring-actuated ringing mechanism concealed therein including a disc having a peripheral notch, a locking member normally engaging the notch so as to render the ringing device inactive having a curved flange thereon and a stationary element engaging the flange when the knob is turned so as to lift the locking member out of its engagement with the disc and to allow the ringing device to become active.

2. A device of the character described, comprising a door knob, a spring-actuated ringing mechanism concealed therein including a disc having a peripheral notch, a locking member normally engaging the notch so as to render the ringing device inactive having a curved flange thereon and a stationary element engaging the flange when the knob is turned so as to lift the locking member out of its engagement with the disc and to allow the ringing device to become active, said stationary member being adapted to be manually moved into an inoperative 100 position.

3. A device of the character described, comprising a shaft centrally supported therein having a bell, a bell ringing mechanism and disc with a peripheral notch mounted thereon, spring means for operating the ringing mechanism, a locking member normally engaging the notch so as to render the ringing device inactive having a curved flange thereon and a stationary element engaging the flange when the knob is turned so as to lift the locking member out of its engagement with the disc and to allow the ringing device to become active.

4. A device of the character described,

comprising a shaft centrally supported therein having a bell, a bell ringing mechanism and disc with a peripheral notch mounted thereon, spring means for operating the ringing mechanism, a locking member normally engaging the notch so as to render the ringing device inactive having a curved flange thereon and a stationary ele-

ment engaging the flange when the knob is turned so as to lift the locking member out of its engagement with the disc and to allow the ringing device to become active, said stationary member being adapted to be manually moved into an inoperative position. 10

EARL B. CALDERWOOD.
